MACHINE DRIVE

Boyd R. Abbott, Norristown, Pa., assignor to Armstrong Cork Company, Lancaster, Pa., a corporation of Pennsylvania

Application April 10, 1943, Serial No. 482,644

6 Claims. (Cl. 74—221)

1

This invention relates to a machine drive and more particularly to a drive for imparting a predetermined intermittent motion to a machine to be driven, with provision for varying the time interval between intermittent moves of the machine. The drive has particular usefulness in rotary type forming machines such as that disclosed in my application Serial No. 482,645, filed April 10, 1943, entitled "Forming machine" wherein a plurality of molds are intermittently moved into a series of stations positioned along the path of travel of the molds and at these stations operations are performed to produce the final product. In this machine, it is desirable to move the train of molds as quickly as possible between stations but to permit a relatively longer dwell in the various stations for some of the operations to be performed consume considerable time.

With the device of the present invention, it is possible to impart a relatively rapid movement to the machine and to control the starting of the drive by an electrical timer or manually so that the time interval between intermittent motions of the drive may be of any desired length.

The drive is designed to be useful to transmit considerable power, for in devices such as the forming machine referred to above, many horsepower are required to rotate the machine, and particularly to start rotation.

The invention will be described in connection with the attached drawing in which

Figure 1 is a top plan view of the drive arrangement as applied to a rotary machine of the type disclosed in my copending application above identified.

Figure 2 is a detail view of the electrical switch arrangement;

Figure 3 is a sectional view taken on the line 3—3 of Figure 1 and showing the driving pin aligning arrangement; and

Figure 4 is a wiring diagram showing a typical electrical control arrangement.

Referring to Figure 1 the drive consists essentially of a motor 2 which drives a pair of sprockets 3 through a gear reduction 4 which is connected to the motor 2 through a sprocket 5, a chain 6, and a sprocket 7 affixed to the drive shaft of the motor 2.

The sprockets 3 drive a pair of belts 8 in the form of roller chains, the paths of travel of both chains being identical but in different horizontal planes. The path of travel of the chains 8 is determined by pairs of idler sprockets 9, 10, and 11. The sprockets 9 and 11 are fixed in permanent position but the sprocket 10 is adjustable to

align the driving pins as will fully be described later.

In Figure 1 the machine to be driven is generally indicated by the numeral 12 and in this embodiment takes the form of a circular band 13 (shown in section in Figure 3) having a series of posts 14 uniformly spaced about the circumference of the band, two posts 14 being shown in Figure 1. These posts 14 are effective for transmitting power from the chains 8 to the band 13 to rotate the machine 12, the magnitude of movement on each intermittent operation of the drive being equivalent to the space between adjacent posts 14.

As shown in Figures 2 and 3, a driving pin 16 is attached to the two chains 8 so as to span the space between them. The driving pin 16 is disposed vertically between the two horizontal runs of chain 8 (see Figure 3). In the embodiment shown, there are two such driving pins 16 spaced at points 17 and 18 as indicated in Figure 1. The pins 16 are positioned to engage the posts 14 and by such engagement move the machine 12 in the direction of the arrow in Figure 1; that portion of the run of the chains 8 between the idler sprockets 10 and 11 parallels the path of movement of the machine 12, and as the pin 16 at location 18 moves about the sprocket 11, it is disengaged from the post 14 and movement of the machine is arrested until the pin at location 17 comes into engagement with the next rearward post 14 adjacent the sprocket 10 upon the next intermittent motion of the drive. The pins 16 automatically disengage from the posts 14 because the chains 8 to which they are attached run in a direction substantially parallel to the surface of the post which is engaged by the driving pin as the chains 8 pass about the sprocket 11.

To insure that the driving pins 16 will properly approach and engage the posts 14, the pair of sprockets 10 is mounted for adjustment in a forked bracket 19 pivoted about the bolt 20. A lug 21 (Figure 3) is fixed to the bracket 19 and is provided with an opening 22 through which passes a threaded adjusting bolt 23 (Figure 1). One end of the bolt 23 is fixed to an angle support 24 and the opposite end is received in the opening 22. Adjusting nuts 25 and 26 are provided on the bolt 23 and the position of the sprockets 10 is determined by movement of the nuts 25 and 26 which are effective for rotating the bracket 19 about the pivot 20.

In order to compensate for any change in the tension on the chains 8 due to adjustment of the sprockets 10 and to insure that the proper tension

is always applied to the chains, a pair of tightening sprockets 25' is provided affixed to the bracket 26' and an adjusting bolt 29 is secured to the machine frame. An adjusting nut 30 is effective for rotating the bracket 26' about the pivot 27 to move the tightening sprockets 25' toward or away from the chains 8. A locking nut is provided on the opposite side of the lug 28 but this is not shown in Figure 1, it being disposed below the top of the bracket 26'.

The spacing of the posts 14 is uniform throughout the entire circumference of the rotary machine to be driven and the movement accomplished upon each intermittent operation of the drive is equivalent to the distance between the surfaces of the posts which are engaged by the driving pins 16, so that upon each intermittent motion of the drive, the machine is rotated for a portion of a revolution, each portion being of the same magnitude. Thus, the machine may be intermittently moved by rotating the driving chains 8 continuously, the period of dwell being determined by the speed of rotation of the chains 8 and the spacing of the driving pins 16 at points 17 and 18. In most intermittent drives, however, it is desirable to provide for a much longer dwell than would be possible with a relatively compact drive for, if a long dwell is required, the machine must be either rotated very slowly or a relatively long pair of chains 8 must be provided so that the driving pins 16 may be spaced a considerable distance apart. The motion of the machine 12 will of course cease upon movement of the pin 16 which happens to be in engagement with a driving post 14 out of engagement therewith and further motion will be effected only when another pin engages the next driving post 14 spaced to the rear in the direction of travel of the machine to be driven.

The timing of the drive may be conveniently controlled electrically to start and stop the motor 2. This is illustrated in Figures 1 and 2 where a limit switch 31 is provided having a contact arm 32 carrying a roller 33. The arrangement of the switch 31 is such that when the arm 32 is rocked, the circuit which it controls will be broken but will be made again as soon as the arm 32 returns to its normal position. A control pin 34 is mounted on the upper run of chain 8 and the limit switch 31 is adjustably mounted upon a bracket 65 to bring the roller 33 into the path of travel of the pin 34 so that upon movement of the pin 34 past the station at which the switch 31 is located the pin 34 will rotate the arm 32 breaking the circuit, but as soon as the roller 33 passes over the pin 34, the switch 31 will again be in closed position. As shown in Figure 2 the pin 34 is mounted in the same position as the driving pin 16 and one control pin will be provided for each driving pin 16 so as to stop the motor 2 upon each movement of the drive equal to the distance between the posts 14.

Figure 4 is a wiring diagram showing a typical arrangement for controlling the motor 2. Current is fed from the source S directly to one side of the motor 2 and the other side of the source is controlled by the switch 31. A magnetic switch 36 is effective for completing the circuit from the source S to the motor 2 when the switch 31 is closed. In order to energize the magnetic switch 36 a push button 37 is provided which closes the circuit for the switch 36 whereupon its contact arm 38 will be elevated and the circuit for the motor 2 will be completed. The push button 37 may be then released and the

motor 2 will run until control pin 34 on chains 8 engages the roller 33 on contact arm 32 of switch 31, whereupon current from the source S to the magnetic switch 36 will fail and contact 38 will immediately open, stopping motor 2. Contact arm 38 cannot be brought into engagement to start motor 2 until push button 37 has been pressed, completing the circuit for magnetic switch 36.

In most cases the push button 37 will be replaced by an automatic timer indicated in dotted lines in Figure 4 and designated AT which will periodically close the circuit for the magnetic switch 36, thus starting up the motor 2 and causing a motion of the drive to be effected equivalent to the distance between the driving posts, the drive being automatically stopped by the limit switch 31. If desired, safety switches may be provided on the machine to complete the timer circuit only when the various operating devices positioned along the path of travel of the machine have been properly cleared.

While I have illustrated and described a preferred embodiment of my invention, it will be understood that the same may be otherwise embodied and practiced within the scope of the following claims.

I claim:

1. In a drive for a member to be driven having a series of spaced posts associated therewith to be engaged by driving means, driving means comprising a driven endless conveyor moveable for a portion of its run along the path of travel of the member to be driven, a driving pin carried by said conveyor and engageable with a post associated with the member to be driven to impart motion to said member, an electric motor for driving said conveyor, and means for automatically controlling the movement of the conveyor comprising a magnetic switch for controlling the supply of current to said motor, a limit switch in circuit with the magnetic switch for interrupting the supply of current thereto to cause said magnetic switch to open and interrupt the supply of current to said motor, a normally open switch in circuit with said magnetic switch for connecting the magnetic switch in circuit with the current source of supply therefor, a timer for periodically closing said normally open switch, and tripping means carried by said conveyor for actuating said limit switch upon completion of each intermittent movement of said member to be driven.

2. In a drive for a member to be driven having a series of equally spaced posts carried by said member to be engaged by driving means, driving means comprising a driven endless conveyor moveable for a portion of its run along the path of travel of the member to be driven, a drive pin carried by said conveyor and engageable with a post associated with the member to be driven to impart motion to said member, an electric motor for driving said conveyor, and means for automatically controlling the movement of the conveyor comprising a magnetic switch, a limit switch, and a normally open timer controlled switch, the operating winding of said magnetic switch being connected to one side of a source of current through said limit switch and to the other side of said source through said timer controlled switch and motor, said operating winding holding said switch in circuit making condition only so long as said limit switch is closed and the motor operating, automatically falling to circuit breaking condition upon actuation of said limit

switch, and means carried by said conveyor for tripping said limit switch upon completion of each cycle of movement of the member to be driven.

3. In a drive for a member to be driven having a plurality of equally spaced posts to be engaged by driving means, driving means comprising an endless conveyor having a portion of its run along the path of travel of the member to be driven, a plurality of equally spaced driving pins carried by said conveyor and sequentially engageable with said posts to move said member to be driven a distance equivalent to the distance between the driving posts on each sequential movement of the drive, means for automatically controlling the movement of the conveyor comprising an electric motor for driving said conveyor, a magnetic switch for controlling the supply of current to said motor, a limit switch in circuit with said magnetic switch for interrupting the supply of current to said magnetic switch to cause the same to open and interrupt the supply of current to the motor, a normally open switch in circuit with said magnetic switch for connecting the magnetic switch in circuit with the source of current supply therefor, actuating members carried by said conveyor and effective for tripping said limit switch to interrupt the supply of current to said magnetic switch and thereby break the circuit for the source of supply of current to the motor, one switch actuating member being provided for each driving pin so as to stop said conveyor after each intermittent move of the member to be driven equivalent to the distance between the posts carried by the member to be driven.

4. In a drive for a member to be driven having secured to said member spaced posts to be engaged by the driving means, driving means comprising a pair of spaced chains having parallel runs in different planes, means for moving said chains in a closed path, a driving pin connected to said chains and engageable with a post on said member to be driven to impart motion to said member, means for directing said chains along a portion of their runs in a direction substantially parallel to the surface of the post which is engaged by the driving pin to bring said pin into position for engagement with said post close to the point of connection of said post to said member, and means for moving said chains along an adjacent portion of their runs in a direction substantially along the path of travel of said member

to impart motion to said member after engagement of said pin with said post.

5. In a drive for a member to be driven having secured to said member spaced posts to be engaged by the driving means, driving means comprising a pair of spaced chains having parallel runs in different planes, means for moving said chains in a closed path, a driving pin connected to said chains and engageable with a post on said member to be driven to impart motion to said member, means for directing said chains along a portion of their runs in a direction substantially parallel to the surface of the post which is engaged by the driving pin to bring said pin into position for engagement with said post close to the point of connection of said post to said member, and means spaced from said first named means for directing said chains along a portion of their runs in a direction substantially parallel to the surface of the post which is engaged by the driving pin to withdraw the pin from engagement with said post.

6. In a drive for a member to be driven having secured to said member a plurality of posts equally spaced about the periphery of said member, driving means comprising a pair of spaced chains having parallel runs in different planes, means for moving said chains in a closed path, a plurality of driving pins connected to said chains and sequentially engageable with said spaced posts on said member to be driven to impart motion to said member, means for directing said chains along a portion of their runs in a direction substantially parallel to the surface of a post which is to be engaged by a driving pin to bring said pin into position for engagement with said post close to the point of connection of said post to said member, means for moving said chains along an adjacent portion of their runs in a direction substantially along the path of travel of said member to impart motion to said member after engagement of said pin with said post, and means spaced from said first named means a distance equivalent to the distance between spaced posts on said member to be driven for directing said chains along a portion of their runs in a direction substantially parallel to the surface of the post which is engaged by the driving pin to withdraw the pin from engagement with said post, with the next rearward post in position to receive the next forward driving pin.

BOYD R. ABBOTT.
